BACK MOVEMENT LOCK FOR PAVER BUCKETS

Filed June 7, 1926

2 Sheets-Sheet 2

UNITED STATES PATENT OFFICE.

ERICH H. LICHTENBERG, OF MILWAUKEE, WISCONSIN, ASSIGNOR TO KOEHRING COMPANY, OF MILWAUKEE, WISCONSIN, A CORPORATION.

BACK-MOVEMENT LOCK FOR PAVER BUCKETS.

Application filed June 7, 1926. Serial No. 114,313.

In road and street paving operations today there is commonly employed a concrete mixing machine which is known as a paver and which is really a portable mixing plant, 5 comprising a boom and bucket distributor. The bucket of the boom and bucket distributor transfers the concrete from a point near the mixer to a point near the outer end of the boom, dependent upon the range of 10 distribution desired. At the mixer end of the boom the bucket receives its charge of mixed concrete from the mixing drum, and as the concrete passes down a chute in leaving the mixing drum it exerts considerable force against the bucket as it enters, 15 tending to move the bucket away from the mixing machine.

The present invention provides a locking device for preventing the above unauthorized movement of the bucket and having the additional function of effectively locking the bucket from movement when the boom is operating in a position in which it is downwardly inclined from the mixing 25 machine.

The locking device above referred to is advantageously combined with certain other mechanical features of the machine and arranged to be automatically engaged 30 and disengaged incident to the operation of parts of the machine that are controlled manually or otherwise from the power plant of the paver.

In the accompanying drawings, 35 Figure 1 is a side elevation showing a portion of the frame of a portable mixing machine or paver and a portion of the boom and bucket distributing attachment mounted thereon, the structure illustrated incorporating the locking feature of the invention.

Figure 2 is a fragmentary sectional view bringing out more clearly the manner in which the cam actuator for throwing out the 45 clutch mechanism cooperates with the locking device.

Figure 3 is a top plan view of the locking and clutch actuating member and its mounting on the boom, the view being a section taken above these parts and through the vertical clutch actuating rod.

Figure 4 is a fragmentary side view of

the locking member and its mounting in coaction with the cam actuator aforesaid, dotted lines showing the locking member 55 in disengaged position.

For a full understanding of the machine in connection with which my invention is adapted to be used, reference may be had to my Reissue Letters Patent No. 15,768, 60 dated February 19, 1924, and my Letters Patent No. 1,141,470, issued June 1, 1915. The clutch throw-out mechanism illustrated in this case is similar to that of the reissue 65 patent, and the carriage or trolley which supports the bucket is similar to that which is shown in my other patent above identified.

As those versed in the art to which my invention relates are quite familiar with the construction and operation of paving 70 machines such as illustrated, brief reference only need be made to the main parts of the machine as follows:

In the drawings 1 denotes the mixing drum and 2 the frame work of the machine supporting the same for rotation. 3 denotes the boom of the boom and bucket distributor, and 4 designates the bucket thereof. The bucket 4 is adapted to traverse the boom longitudinally thereof, being supported by hangers 5 carried by a trolley or carriage 6 which has the rollers 7 traveling in the channels of the two channel beams or members that form the fabricated boom structure. The bucket 4 is actuated by 75 cable means 8 connected up therewith in the usual way and adapted to automatically operate certain bottom door mechanism for the bucket 4, not specifically set forth because not material to the invention. There 80 is provided a clutch operating lever 9 which controls the action of certain clutch mechanism like that shown in my reissue patent. Said clutch mechanism is also controlled by a hand lever 10 as well known.

From the mixing drum 1 the concrete aggregates mixed therein are fed to the bucket 4 by a chute 11.

The trolley or carriage 6 is equipped with a cam actuator 12 bolted or otherwise secured thereto near its innermost end, and this cam actuator in my previous constructions of my machine is designed to engage a roller 13 beneath the lower end of a ver-

tical actuating rod 14^a secured to the outer end of the clutch lever 9. In operation as the bucket 4 is moved inwardly on the boom 3 and reaches the point adjacent to the mixing drum 1, in which it is illustrated in Figure 1, the cam 12 rides into contact with the roller 13 and raises the rod 14^a, actuates the lever 9 and disengages the clutch that transmits the driving power to the cable 8 for causing the inward movement of the bucket 4 on the boom 3. In this way the cam actuator 12 "knocks out" or disengages the effective operating clutch aforesaid, which is not fully illustrated, and the movement of the bucket 4 is discontinued just as it arrives at a position beneath the chute 11.

In the practice of my present invention I have formed the cam actuator 12 near the outer end of its cam portion or surface with a hook or shoulder 12^a adapted to cooperate with a pivoted locking member 14 which is pivoted at 15 to a short vertical standard 16 attached to the boom 3. The roller 13 is journaled upon the locking member 14. The free end of the locking member 14 is adapted to engage the hook or shoulder portion 12^a of the cam actuator 12, see Fig. 1 and Fig. 4, and when in such engagement, which takes place automatically as the bucket 4 reaches the inner end of its transverse movement on the boom, the said locking member 14 locks the trolley or carriage 16 from outward movement.

When the lever 10 is thrown in order to engage one of the operating clutches for the cable 8 to cause the outward traverse of the bucket 4 on the boom, the clutch lever 9 is elevated slightly and raises the locking member 14 as well as the rod 14^a and thereby positions the member 14 out of the path of the hook or shoulder 12^a, so that the carriage 6 with its bucket 4 is free to move out on the boom under the operating action of the cable 8 and the clutch made effective by the movement of the lever 10.

The action of the parts in an opposite direction to enable the locking member 14 to become effective has been previously described. It takes place when the carriage 6 reaches the inner end of the boom 3 and the cam actuator 12 engages the roller 13 and lifts the locking member 14 until the latter drops back in front of the hook or shoulder 12^a.

From the foregoing it will be seen that no matter with what force the contents of the drum are discharged into the bucket 4, the said bucket cannot move away from the mixing machine. Likewise, when the boom 3 is downwardly inclined and the natural tendency of the bucket 4 is to gravitate in a direction away from the drum 1, such movement is prevented effectively by coaction of the locking member 14 with the cam actuator 12.

Having thus described my invention what I claim as new and desire to secure by Letters Patent is:

1. In a machine of the class described, a boom and bucket concrete distributing attachment comprising a boom, a bucket, a carriage to travel on the boom and supporting the bucket, clutch knock-out mechanism carried by said carriage, and locking means cooperative with said clutch knock-out mechanism to hold the carriage and its bucket in a predetermined position on the boom. 70

2. In a machine of the class described, a boom and bucket concrete distributing attachment comprising a boom, a bucket, a carriage to travel on the boom and supporting the bucket, clutch knock-out mechanism carried by said carriage, and locking means cooperative with said clutch knock-out mechanism to hold the carriage and its bucket in a predetermined position on the boom, the clutch knock-out means being automatically cooperative with the locking means as the bucket reaches its said predetermined position on the boom. 80

3. A concrete distributing attachment for mixers, comprising a boom, a bucket to travel along the boom, a carriage directly supported by the boom and carrying the bucket, a clutch knock-out cam carried by the carriage, clutch knock-out mechanism cooperative with said cam, and locking means connected with the clutch knock-out mechanism and engageable with the cam to lock the bucket against movement until said locking means is released. 95

4. A concrete distributing attachment for concrete mixers, comprising a boom, a bucket, a carriage to travel along the boom and supporting the bucket, a locking member on the boom, means on the carriage engageable by the locking member on the boom to hold the bucket against movement in one direction on the boom, clutch operating mechanism, and means intermediate the clutch operating mechanism and the locking member for releasing the same and permitting the movement of the bucket previously prevented by said locking member. 105

5. In a boom and bucket distributing attachment for concrete mixers, in combination, a boom, a bucket, a carriage to travel on the boom and carrying the bucket, clutch mechanism for supplying driving power for moving the carriage and its bucket, a cam for actuating said clutch mechanism to render it ineffective and mounted on the carriage, and locking means cooperative with said cam to prevent movement of the bucket 110 until said locking means is released. 120

6. In a boom and bucket distributing attachment for concrete mixers, in combination, a boom, a bucket, a carriage to travel on the boom and carrying the bucket, clutch 130

mechanism for supplying driving power for moving the carriage and its bucket, a cam for actuating said clutch mechanism to render it ineffective and mounted on the carriage, and locking means cooperative with said cam to prevent movement of the bucket until said locking means is released, the cam aforesaid being automatically engageable with the locking member to render the latter operative to act on the cam to prevent its locking function.

7. A concrete distributing attachment for concrete mixers, comprising a boom, a bucket, a carriage to travel along the boom and supporting the bucket, a locking member on the boom, means on the carriage engageable by the locking member on the boom to hold the bucket against movement in one direction on the boom, control means to control movement of the bucket on the boom, and an instrumentality operated by the control means to cause release action of the locking member as the said movement of the bucket is initiated.

25 8. In a concrete-distributing machine, the combination of a boom, a power driven bucket supported to travel on the boom, a locking member cooperative with said bucket to hold the bucket against movement in a predetermined position, and means actuated by locking movement of the locking means for discontinuing delivery of power to the bucket.

9. In a concrete-distributing machine, the combination of a boom, a power driven bucket mounted to move on the boom, a releasable lock for the bucket, and means re-

sponsive to the locking and releasing of the bucket for respectively discontinuing and applying power to the bucket.

10. In distributing attachments for concrete mixers the combination of a boom, a bucket, a carriage mounted to travel on the boom and to support the bucket, locking means on the boom, means on the carriage engageable by the locking means to retain the bucket against movement, means on the carriage to cam the locking means to locking relation with respect to the carriage holding means, and means actuated by such camming action for causing movement of the bucket.

11. In mechanism of the class described, the combination of a bucket mounted to reciprocate, means for supplying power to the bucket for moving the bucket reciprocally, a releasable lock for securing the bucket against movement, and means actuated incident to operation of the lock for controlling application of power to the bucket.

12. In concrete distributing mechanism of the class described, the combination with a boom and a distributing bucket operable therealong, of means for causing travel of the bucket along the boom releasable locking device for holding the bucket immovable in a position on the boom, manual means for effecting release of the locking means, said means being associated with the bucket driving means, and means actuated by locking movement of the locking means for discontinuing delivery of travel causing power to the bucket.

In testimony whereof I affix my signature.
ERICH H. LICHTENBERG.
